(57) **CLAIM**

An ornamental design for a bottle, as shown and described.

DESCRIPTION

FIG. 1 is a front, left, top perspective view of the bottle showing my new design;

FIG. 2 is a right side elevational view thereof, the left side being a mirror image;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a sectional view taken along line 7—7 of FIG. 2 to better show the contours of the design.

The broken line showing in the drawings is for environmental purposes only and forms no part of the claimed design.
